UNITED STATES PATENT OFFICE

1,924,963

STORE

Clarence O. Sherrill, Cincinnati, Ohio, assignor to
The Kroger Grocery & Baking Company, Cincinnati, Ohio, a corporation of Ohio

Application November 4, 1931. Serial No. 572,990

6 Claims. (Cl. 20—1.6)

In the operation of stores, and particularly a group of stores in a given locality, which are supplied with goods from a common warehouse or similar source of supply, it is desirable at times to make deliveries of goods outside of the usual "business" hours in order that the period of delivery may be spread over more time and the delivery facilities, as trucks and men, be more fully and efficiently utilized to the end that the expense of distributing the goods from the warehouse to the stores may be carried on at a minimum cost and a substantial reduction in overhead thus effected. With stores such as grocery stores, for example, with the usual equipment and wherein the goods are displayed around the front of the store it has been found inadvisable to admit delivery crews without the presence of the store manager or a clerk to take care not only of the inventory in the store but to check up the goods delivered, thus insuring that no confusion result and that no loss or inventory will take place.

The object of my said invention is to provide means whereby a section of the front portion or lobby of the store adjacent the entrance may be separated from the remainder in such a way that the trucking or delivery crew may be provided with a pass key to the entrance doors but not be afforded access to the store proper or that portion of the store in which the stock of goods is on display. I accomplish this purpose by providing a portable, collapsible partition so constructed that it may be readily put in place and locked against displacement when the store is closed at night and readily removed and stored out of the way when the store is opened for business and which is adapted to partition off a sufficient space adjacent the store entrance to receive the supply of goods which may be delivered from the warehouse or source of supply and thus make it feasible to provide the delivery man with a pass key to the entrance without admitting the delivery crew to the store proper and exposing its contents to their handling, all as will be hereinafter more fully described and claimed.

Referring to the accompanying drawings, which are made a part hereof and on which similar reference characters indicate similar parts,

Figure 1 is a perspective view illustrating the front portion of a grocery store wherein goods are displayed adjacent the entrance, showing the space adjacent to said entrance partitioned off and separated from the rest of the store by one of my portable and collapsible partitions, the view being from the inside of the store in a direction towards the entrance,

Figure 2, a perspective view illustrating more clearly the construction and arrangement of the partition,

Figures 3, 4 and 5 detail views showing more clearly certain parts,

Figure 6, a view similar to Figure 2 illustrating another form of partition, and

Figures 7, 8 and 9 detail views illustrating other features of construction more in detail.

In the form of partition illustrated in Figures 1 and 2, I provide stanchions or posts 10, the lower ends of which are inserted in sockets 11 set in the floor at appropriately spaced points and the upper ends of which are held in position by guys (as chains or ropes) 12 connected at one end to eyes on the upper ends of said stanchions and to appropriately positioned eyes on floor plates 13 at the other end. The central stanchions 10 are preferably held spaced apart the required distance by a cross bar 14 appropriately connected with their upper ends.

The front stanchions 15 are formed at their upper ends with sockets which engage downwardly turned fingers 16 on plates 17 which are secured on either side of the doorway. Each stanchion 15 is provided with a forwardly projecting arm or clip 18 which mates with a projecting arm 19 on a plate 20 secured to the sides of the door frame intermediate the ends of said stanchion. A lock 21 of appropriate character, shown as a padlock, is inserted through perforations in said stanchions and serves as a means for thus locking the parts in place.

The lower ends of the stanchions are also connected by flexible connections as chains 22 such as shown in Figure 3, which may be secured to the stanchions by securing clips 23 riveted thereto at the corners of the structure. On the framework thus provided is mounted canvas or other flexible material to form a partition which will completely enclose the space adjacent to the entrance doors and separate it from the store proper. A pocket or receptacle 24 is preferably mounted on the inside of the partition in which the person delivering the goods may deposit an invoice or statement showing the items delivered and giving any other information desired and by which the delivery may be checked by the store manager or other person charged with the duty after his arrival at the store.

The upper edge of the partition is preferably reinforced by a rope or cable 25 around which the upper edge of the canvas is secured as best shown in Figure 4. This rope or cable is of sufficient size and strength for the purpose but also is

60

105

110

sufficiently flexible to permit the folding of the partition. It will be understood that either the cable shown in Figure 4 or the chain shown in Figure 3 may be used at both the upper and lower edges of the partition if found desirable. In Figure 3 at points 26, I indicate how the canvas may be stitched to the links of the chain for further security at the corners of the structure.

In Figures 6 to 9, I illustrate a modified form 10 wherein wire mesh sections are employed in lieu of the canvas partition. Each section consists of uprights and cross-members or rods of appropriate size for the purpose covered with wire netting of any appropriate mesh. The upright 15 at one edge of each section is formed with a foot 31 adapted to be inserted in a slot 32 in a floor plate 33 and when turned to normal position as indicated in Figure 9 to be locked beneath said floor plate. The upper end of said upright or rod 20 is provided with an eye 34. The upright on the opposite edge of each section is formed with an upwardly projecting portion 35 which extends a short distance above the normal height of the partition and on its lower end with an eye 36. 25 These details are clearly illustrated in Figure 7. The two panels or sections forming the rear end of the enclosure meet as indicated in Figure 6 and are locked together by an appropriate lock such as a padlock 37. 30 The cage or portable partition is thus formed in two duplicate sections. When it is desired to adjust the partition in place as indicated in Figure 6, the angularly positioned eye 34 of the front section is hooked over hook 38 on the plate 39 35 secured to the side of the door frame. The section is then turned to bring the horizontal foot 31 of the lower end of the upright in line with the slot 32 in the floor plate 33 immediately beneath when said foot passes through said slot and the 40 section is then turned in position to bring its eye immediately above the floor plate 33 positioned to receive the foot of the next section. The next section is put in place by mounting the eye 34 on the upper corner thereof over the projecting end 45 35 of the upright of the first section, inserting the foot through the eye 36 on the lower end of said upright and then inserting said foot through the slot in the floor plate immediately beneath and turning the section to lock said foot and section 50 in place. Each section is thus secured to the adjacent section and locked to the floor until the rear sections are reached when they are brought together as indicated in Figure 6 and secured together by the lock 37, as before described. 55 In the form shown in Figures 1 to 5 wherein the canvas is employed in lieu of the wire netting, the parts are put in place by setting the stanchions in the floor plates, engaging the upper ends of the front stanchions 15 with the fingers 16 which 60 brings the plates 18 and 19 together and inserting the padlock 21 through the perforations in said plates by which means the partition is securely held in place and its purpose accomplished. To 65 remove the partition it is only necessary to unlock the padlock and disengage the parts, folding up each side of the partition section upon section and placing it in an appropriate place out of the way during the business hours or while the store is open for customers. In taking down the form 70 shown in Figures 6 to 9 it is only necessary to unlock the padlock 37, turn each section to bring the foot on the upright in line with the slot in the floor plate and lift the foot out of said slot thus freeing the section when each side of the 75 cage may be folded as before described, the con-

nections between the sections being hinged connections as will be readily seen.

By such arrangement it is entirely feasible to entrust pass keys to the men charged with delivery from the warehouses and the work of delivering goods may be begun at a very early hour in the morning before the store is opened for business or it may be continued after the store is closed at night and a single truck and crew thus be enabled to supply the goods to a very much larger number of stores than would be possible where delivery is limited to the stores when the store managers and clerks are on duty, thus effecting a substantial saving in cost of delivery and contributing largely to the economy of operation of a system or chain of stores provided with this invention.

Having thus fully described my said invention, what I claim as new and desire to secure by Letters Patent, is:

1. A portable and collapsible partition structure for the purpose described comprising uprights removably mounted in sockets in floor plates appropriately positioned around the space to be partitioned off in a store, flexible connections connecting said uprights at their upper and lower ends, means for appropriately supporting the structure, flexible material mounted upon said connections of the structure, attachments for connecting the front ends of the side members of the structure to the door frame of the store, and a lock for securing the structure in place, substantially as set forth.

2. A portable collapsible partition for dividing a space adjacent the entrance from the remainder 110 of the store comprising sections foldably connected one with another, means for detachably securing the front section on each side to each side of the entrance door and to the floor of the store, means for securing each section to the floor of the store, and means for locking said several sections together to provide a secure cage around said space, whereby it may be utilized for the reception of merchandise without permitting 115 access to the remainder of the store by those having access to said space, substantially as set forth.

3. The combination with a store for the sale of merchandise, of a collapsible partition adapted and arranged to separate from the remainder of the store a space adjacent to its entrance, means for securing said partition in place to divide said space from the remainder of the store with the door of the store opening into the space thus 125 partitioned off from the remainder, whereby the portion of the store containing the normal inventory may be so separated from the space adjacent the entrance that goods may be delivered within the store and inside the door at the entrance to the store without permitting access 135 from said entrance to the inventory in the remainder of the store.

4. A store provided with a door-way, a closure for said door-way, furniture within said store for use in displaying and selling the merchandise, a collapsible partition secured to the respective sides of the door-way and extending back into the store to separate a space adjacent the door-way from the remainder of the store, and means 140 for locking said partition in position, whereby a store is provided having a space adjacent the door-way for receiving goods effectually separated from the remainder of the store so that the normal inventory therein is inaccessible to 150

the parties delivering the goods.

5. A compartment of the character described including a stationary portion having a floor and a door and a movable partition comprising a plurality or series of sections, the sections whereof respectively have releasable interlocking securing means as part of said respective sections at the respective ends of said sections, said securing means of each section arranged to interlock with the securing means of its neighboring section, co-acting securing means co-acting with said interlocking securing means at the respective ends of said series of sections at the respective sides of said door, said co-acting securing means having attachment with said stationary portion, anchor parts having attachment with said floor, and co-acting anchor parts at the bottoms of said respective sections, said first named co-acting securing means and said anchor parts constructed

to resist separating movements between said sections, and said anchoring parts constructed to resist upward movements of said respective sections.

6. A portable and collapsible partition structure for the purpose described comprising uprights removably secured to the floor and appropriately positioned around the space to be partitioned off in a store, foldable connections connecting said uprights at their upper and lower ends, means for appropriately supporting the structure, foldable material mounted upon said connections of the structure, attachments for connecting the front ends of the side members of the structure to the front of the store at each side of the entrance door, and a lock for securing the structure, substantially as set forth.

CLARENCE O. SHERRILL.
